UNITED STATES PATENT OFFICE.

WILLIAM HUCKS, OF LONDON, ENGLAND, ASSIGNOR OF ONE-HALF TO SODASTREAM LIMITED, OF CAMDEN TOWN, ENGLAND.

APPARATUS FOR AERATING LIQUIDS.

Application filed July 30, 1925, Serial No. 47,038, and in Great Britain September 27, 1924.

This invention is a modification of, or improvement upon, the invention described and claimed in the specification of application for Letters Patent Serial No. 733,020 filed August 19, 1924 and has for its principal objects to simplify the mechanism and its operation and to avoid the use of the gland through which the piston rod slides and also to minimize friction in the moving parts, and to render the apparatus very compact and conveniently operated.

According to this modification, or improvement, the receptacle in which the liquid is aerated, is open at its lower end, and the piston-like body, which is movable in the said receptacle, is connected through a yoke, or other suitable connection, to a lever fulcrumed to some fixed part of the apparatus. The said lever is operated from a shaft mounted in fixed bearings and provided with means by which it can be given rotary movement in one direction so as to raise the movable body in the receptacle and discharge the aerated liquid therefrom and, by continued movement, lower, or allow the descent of, the said movable body in the said receptacle in readiness to discharge liquid at the next operation of the machine. The said shaft can also be provided with means by which, during its rotary movement, the combined outlet and safety valve and the counting device, or either of them, can be operated and means are provided by which the shaft is prevented from being turned in the reverse direction and there is, preferably, also provided a locking device liberated by the gas under pressure so that the apparatus cannot be operated until gas is admitted to the receptacle.

There may also be provided modified means, as hereinafter described, for preventing the liquid to be aerated from passing out of the receptacle owing to siphoning action set up by the discharge of the aerated portion of liquid.

I will describe my invention with reference to the accompanying drawings, which illustrate an apparatus constructed in accordance therewith.

Figure 1 is an elevation shewing the parts in the position when the piston is at the bottom of its stroke and Figure 2 is a vertical section shewing the parts in the position when the piston is at the top of its stroke. Figure 3 is a plan of Figure 1 with the inverted spherical bottle removed and Figure 4 is a horizontal section taken approximately on the line *a*, *a*, Figure 1.

The receptacle in which the liquid is aerated, consists of a vertical cylinder 1 within a vessel 2 containing liquid to be aerated supplied from a reservoir shewn as an inverted spherical bottle 3 supported on a hinged top, or cover, 4 at one end of the said vessel 2, the neck of the said bottle dipping into the liquid in the said vessel to an extent necessary to maintain the liquid at the predetermined level. The top, or cover, 4 can be turned on its hinge to bring the bottle 3 secured thereto into position to be charged with liquid, and to prevent escape of the said liquid from the bottle whilst the hinged top, or cover, is being returned to its normal position, a stopper 5 is provided which can, from the outside of the said top, or cover, be removed from the mouth of the said bottle when in its inverted position.

The cylinder 1 is open at its lower end and contains the piston-like body which consists of a piston 6, of smaller diameter than the interior of the said cylinder, having secured to its upper surface a flexible valve 7 opening upwards as in the apparatus described and shewn in the specification and drawings of my aforesaid prior application. The rod 8 of the piston 6 passes through a guide 9, formed in one with a piece 10 constituting a stop for the said piston. The piston 6 is reciprocated in the cylinder 1 by a lever 11 pivotally mounted in bearings 12 formed in side brackets 13 secured to a plate 14. The plate 14 is secured to the top of the cylinder 1 and constitutes a cover for the portion of the vessel 2 not covered by the hinged top, or cover, 4, and the said plate has formed thereon a downwardly projecting hollow part 14^a which fits in and limits the capacity of the cylinder 1.

The plate 14 extends beyond the end of the vessel 2 remote from the hinged top, or cover, 4 and on this extension parts of the mechanism of the apparatus, hereinafter referred to, are carried. The end of the lever 11 is connected to the lower end of the piston rod 8 by a yoke, consisting of an upper cross-bar 15 with which the said lever engages and a lower cross-bar 16 to which the said lower end of the piston rod is attached, the said cross-bars being connected by rods 17 which pass through openings in the plate 14. The lever 11 is operated by a cam 18 secured to, or formed in one with, a shaft 19 mounted in bearings 20 on the side brackets 13, the said shaft having a handle 21 for rotating it. Partial rotary movement, in one direction, of the shaft 19 causes the cam 18 to actuate the lever 11 and raise the piston 6 in the cylinder 1 thereby discharging from the said cylinder the liquid which is above the valve 7 of the said piston and draws in a fresh charge of liquid, or allows a fresh charge of liquid to flow, beneath the said piston, into the said cylinder. Continued movement of the shaft 19 in the same direction causes the cam 18 to allow the piston 6 to descend by gravity through the liquid in the cylinder 1 in readiness for the next operation of the apparatus.

The liquid and any surplus gas passes through a valve controlled passage 22 in communication with a space 23 in the upper end of the cylinder 1, into an annular space 24 surrounding the valve seating from which annular space it passes through a drawing off spout 25. The valve controlling the passage 22 is a combined discharge and safety valve consisting in, or comprising, two parts 26 and 27 with a spring 28 between them as described and shewn in the specification and drawings of my said prior application and it is caused to be opened and closed at the proper times by the rotation of the shaft 19 as hereinafter described. The annular space 24 is formed in a protuberance 29 formed on the side of the cylinder 1 beneath the portion of the plate 14 projecting therefrom, and to the outer side of this protuberance is secured a tubular piece 30 constituting a guard and guide for the aforesaid combined discharge and safety valve.

The part 26 of the combined discharge and safety valve is secured to, or formed in one with, a screwed rod 31 engaging a nut 32 on a piece 33 depending, through slots 34 in the plate 14, from another plate 35 slidable on the said plate 14. The nut 32, depending piece 33, and plate 35 are preferably formed in one piece. Reciprocal movement of the plate 35 causes the combined discharge and safety valve to open and close the passage 22 which is in communication with the interior of the cylinder 1

and this is effected at the proper times by cams 36, secured to the shaft 19, which engage upstanding pieces 37 formed in one with the plate 35. The upstanding pieces 37 are arranged one on each side of the cam 36, so that at each complete rotation of the shaft 19 the plate 35 is caused to make one complete reciprocal movement. The aforesaid movement of the slidable plate 35 can also be caused to actuate a counter 38 to indicate the total number of portions of liquid aerated, which may be done by securing the said counter to the said slidable plate and causing the lever 39 of the counter to engage, or come into contact with, a hole 40 in the stationary plate 14 so that at each reciprocal movement of the said slidable plate the said lever will be actuated. In Figures 1 and 2 the counter is shewn protected by a casing 41 having an aperture 42 therein through which the figures of the counter can be seen, but in Figure 3 the said casing is presumed to be removed in order to shew the counter and its actuating lever more clearly. As there may be occasions when it is necessary to discharge non-aerated liquid from the cylinder without rotating the shaft 19 this can be done by unscrewing the rod 31, which is provided with a hand-wheel 43 for this purpose, thereby withdrawing the part 27 of the combined discharge and safety valve from its seating so that the liquid can be discharged, through the drawing off spout 25 by raising the yoke connected to the piston-like body 6. If desired an outlet 44 may be provided at the bottom of the vessel 2 for emptying it when required; any suitable means may be provided for normally closing the said outlet, I have shewn a stopper 45 inserted therein for this purpose.

In order to lock the apparatus and prevent its operation until gas has been admitted to the cylinder 1, the shaft 19 has lugs, or stops, 46 secured thereto, or formed in one therewith, which normally engage projections 47 formed on the forked end of an arm 48 of a bell-crank lever pivoted to the plate 14, the other arm 49 of which is connected to a plunger 50 capable of sliding in a cylinder 51 in communication, by the passage 52, with the cylinder 1 in such manner that, on the admission of the aerating gas through the pipe 53 to the said cylinder, a portion of the gas, or the liquid under the pressure of the gas, passes through the said passage 52 into the cylinder 51 and the plunger 50 is moved downwards in the said cylinder causing the said bell-crank lever to be actuated so as to release the projections 47 on its arms 48 from the lugs, or stops, 46 and allow the shaft 19 to be turned by the handle 21. The arm 49 of the bell-crank lever is controlled by a spring 54 so that after the piston-like body 6 has been

raised and discharged aerated liquid from the cylinder 1 the projections 47 are in position to re-engage the lugs, or stops, 46, and lock the apparatus until the admission of gas again releases it. The arm 49 of the bell-crank lever is connected to the rod 55 of the plunger 50 by a yoke which is shewn as consisting of an upper bar 56, in engagement with the said arm 49 and a lower bar 57, connected to the end of the said plunger rod 55, the said bars 56 and 57 being connected by bars, or rods, 58.

In order to prevent liquid from continuing to flow through the drawing off spout 25 after the discharge of the portion which has been aerated and before the valve has been moved back onto its seating the annular space 24 surrounding the valve seating may communicate with the air outside the apparatus by a passage, or passages, additional to the said drawing off spout, so that, as soon as the aerated liquid has been discharged from the cylinder 1, the siphoning action is arrested by the admission of atmospheric air into the annular space 24. The admission of atmospheric air to the annular space 24 is shewn as being effected by a passage 60 and with the atmospheric air by a passage 61 (see Figure 4) which leads into the space above the liquid contained in the vessel 2.

Secured to the shaft 19 is a ratchet-wheel 62 with the teeth of which a pawl 63 engages to prevent back movement of the handle 21 by the operator. The pawl 63 is normally held in engagement with the teeth of the ratchet wheel 62 by a weight 64 formed in one with the said pawl.

65 indicates a piece carrying the gas pipe 53, the said piece having a screw-threaded part 66 for connecting thereto a gas container (not shewn) and 67 indicates a tray for catching any liquid that may drip from the drawing off spout 25.

45 The operation of the apparatus is as follows:—Presuming the parts to be in the position shewn in Figure 1, gas under pressure is first admitted by the pipe 53 to the cylinder 1 and aerates the liquid therein and 50 under the gas pressure the flexible valve 7 is flattened out and as its diameter is a little more than that of the interior of the said cylinder it makes a pressure-tight joint between the piston and cylinder wall. If 55 there be any excessive pressure it will be relieved by the yielding of the spring 28 of the combined discharge and safety valve. Some of the pressure in the space 23 in the upper end of the cylinder 1 60 passes through the passage 52 and forces the plunger 50 downwardly in its cylinder 51 thereby turning the bell-crank lever 48, 49, on its pivot so that the projections 47 thereon are moved out of engagement with the lugs, or stops, 46 and thereby

70 permit the handle 21 to be rotated in the direction of the arrow *b* shewn in Figures 1 and 2. Upon the rotation of the handle 21 in the aforesaid direction the cams 36 on the shaft 19 operate to move the combined discharge and safety valve off its seating to first release any gas not absorbed by the liquid and then the cam 18 on the said shaft operates to move the piston-like body 6 upwards in the cylinder 1 so that the aerated 75 liquid is forced out of the said cylinder through the passage 22 and the drawing off spout 25 into the glass, or other receptacle placed to receive it. When the aerated liquid has been discharged from the cylinder 1 the parts of the apparatus will be in the position shewn in Figure 2, and on continued movement of the handle 21 the said parts will be returned to the position shewn 80 in Figure 1 in readiness for a succeeding 85 operation of the apparatus.

I declare that what I claim is:—

1. Apparatus for aerating liquids comprising a receptacle open at its lower end, a piston-like body within the receptacle for 90 discharging aerated liquid, a lever fulcrumed at one end to a fixed part of the apparatus, and means connecting the other end of said lever to said piston-like body, in combination with an operating shaft mounted upon the apparatus, and means associated with the shaft and with the lever, whereby through rotary motion of the shaft in one direction said piston-like body may be raised in said receptacle to discharge the liquid 95 therefrom, and through continued rotation of the shaft in the same direction said body may be lowered in said receptacle to a position ready to discharge a fresh quantity of the liquid at the next operation of the apparatus.

2. In an apparatus in accordance with claim 1, means actuated by the rotation of the operating shaft in one direction whereby the valve controlling the outlet passage from 100 the receptacle is moved off and onto its seating during each complete rotation of said shaft, substantially as hereinbefore described.

3. In an apparatus according to claim 1, 110 a slideable piece having the valve controlling the outlet passage from the receptacle attached thereto and a cam, secured to the operating shaft, adapted to move said slideable piece backward and forward whereby 115 said valve is moved off and onto its seating during each complete rotation of said shaft, substantially as hereinbefore described.

4. In an apparatus according to claim 1, 120 a slideable piece to which a valve controlling the outlet passage is attached, a counting mechanism attached to said slideable piece and having an actuating lever adapted to be engaged by a stationary part of the apparatus during each reciprocal movement of 125 130

said slidable piece whereby said counting mechanism is caused to be operated; substantially as hereinbefore described.

5. In an apparatus in accordance with claim 1, a locking device, liberated by gas under pressure, adapted to prevent the rotation of the operating shaft until the gas is

admitted to the receptacle containing the liquid to be aerated; substantially as hereinbefore described.

In testimony whereof I have signed my name to this specification.

WILLIAM HUCKS.
